UNITED STATES PATENT OFFICE.

ROBERT LINDSY, OF CANTON, ILLINOIS.

MAIL BOX.

Application filed July 13, 1921. Serial No. 484,523.

To all whom it may concern:

Be it known that I, ROBERT LINDSY, a citizen of the United States, residing at Canton, in the county of Fulton and State of Illinois, have invented certain new and useful Improvements in Mail Boxes, of which the following is a specification, reference being had to the accompanying drawings.

This invention relates to mail boxes and has for its object to provide a device of this character capable of automatically delivering the mail when the cover of the box is opened.

It is another object of the invention to provide a device of this character wherein means are provided for movably supporting the mail within the box, said means being operatively connected to the cover or lid of the box so as to project the mail when the cover is opened or raised.

It is also an object of the invention to provide a device of this character wherein the mail delivering means also serves to hold the cover in its raised position while the mail is being inserted.

With these and other objects in view the invention consists in the improved construction and arrangement of parts to be herein-after more particularly described, fully claimed and illustrated in the accompanying drawings, in which:

Figure 1 is a longitudinal sectional view of a mail box constructed in accordance with an embodiment of the invention,

Figure 2 is a front elevation with the cover of the box raised,

Figure 3 is a longitudinal sectional view with the cover of the box raised, and

Figure 4 is a section taken on the line 4-4 of Figure 1.

Referring to the drawings, 5 designates a casing or mail box open at one end, the sides of the box at said open end being tapered upwardly toward the top of the box. A cover or lid 6 is hinged at its upper end to the top of the box and is adapted to extend over the open end to close the same. The cover 6 is provided with flanges 7 adapted to extend over the edges of said open end to prevent the entrance of the elements. The lower portion of the cover extends below the bottom of the box to provide opening means for the cover.

In order to position the mail within the box so that it may be readily removed when

the cover is opened without the necessity of the operator extending the hand into the box, there is provided novel mail holding means embodying a shaft 8, adapted to extend laterally of the box, the ends 9 and 10 of the shaft extending through the sides of the box and then positioned at right angles to the main portion of the shaft to prevent disengagement of the shaft from the box. Projecting from the intermediate portion of the shaft 8 is an arm 11 having an eye 12 in its end. The arm 11 is adapted, when the lid is closed, to extend downwardly from the shaft, and to also terminate in spaced relation to the bottom of the box. Projecting from the intermediate portion of the arm 11 and substantially at right angles to the arm, is a holding member 13 having an eye 14 in its end, the eye 14 being disposed above the eye 12.

A mail holding arm 15 is provided, one end of said arm being coiled around the end of the arm 11 and through the eye 12, while the intermediate portion of the arm is disposed in the eye 14. The end portion 17 of the arm 15 projects beyond the eye 14 and is formed into a mail holding hook 18. To permit actuation of the mail holding means upon raising the cover, a connecting rod 19 is provided, one end of said rod being coiled about the eye 14 above the arm 15, the rod being longitudinally curved so as to clear the edge of the top of the box. The end 20 of the rod is pivotally connected to an eye 21 carried by the intermediate portion of the cover 6 adjacent its upper end.

In use, the cover is raised, and through the medium of the connecting rod 19, the holding arm 15 is extended beyond the open end of the box. The mail may then be engaged with the hook 18 and the cover lowered, thereby causing the connecting rod to oscillate the shaft 8 and move the mail holding arm inwardly of the box. When the cover is raised by a person desiring the mail, the same operation takes place, that is, the end 17 of the mail holding arm is directed outwardly of the box so as to permit the operator to remove the mail without inserting the hand in the box.

From the foregoing it will be readily seen that this invention provides novel means for receiving and holding mail within convenient reach of the person using the box, so that the mail may be quickly removed. It

also provides means for the protection of the mail in case the mail box leaks or is damaged, as the mail is held in spaced relation to the bottom of the box. Another important feature of this mechanism is that in view of the longitudinal curvature of the connecting rod 19 and the fact that the eye 14 of the holding member 13 is disposed substantially in alignment with the edge of the top of the box, when the lid is raised, the connecting rod serves to hold the lid in its raised position, as the end 20 of the rod is positioned beyond the center of gravity so that danger of the lid accidentally falling while the mail is being removed is prevented.

What is claimed is:

1. A mail box of the character described comprising a box, a cover movably connected to the box, a shaft rotatably mounted within the box, an arm carried by the shaft, mail holding means carried by said arm, and means for operatively connecting said mail holding means to the cover for oscillating the shaft upon movement of the cover, whereby said mail holding means is moved inwardly and outwardly of the box.
2. A mail box of the character described comprising a box, a cover hinged to the box,

a shaft rotatably mounted within the box, 30 an arm carried by the shaft, a mail holding member connected to the end of the arm, a holding member carried by the arm of the shaft for holding said mail holding arm in angular relation to the arm of the shaft, and 35 a rod connected to said means and to the cover for disposing said mail holding member in an inclined position when the cover is raised.

3. A mail box of the character described 40 comprising a box, a cover hinged to the box, a shaft rotatably mounted within the box, an arm carried by the shaft, a mail holding member connected to the end of the arm, a holding member carried by the arm of the 45 shaft for holding said mail holding arm in angular relation to the arm of the shaft, and a longitudinally curved rod connected at one end to said mail holding member of the arm of the shaft, the opposite end of said member being connected to the cover of the box, said last mentioned end of the rod being disposed to one side of the center of gravity when the cover is disposed in its raised position.

In testimony whereof I hereunto affix my signature.

ROBERT LINDSY.
